RADIATOR

Filed Oct. 10, 1925

INVENTOR:
NORMAN WALKER,
BY *John J. Morris*
HIS ATTORNEY.

UNITED STATES PATENT OFFICE

NORMAN WALKER, OF LOCKPORT, NEW YORK, ASSIGNOR TO HARRISON RADIATOR CORPORATION, OF LOCKPORT, NEW YORK, A CORPORATION OF NEW YORK

RADIATOR

Application filed October 10, 1925. Serial No. 61,830.

This invention relates to radiators and comprises all the features of novelty herein disclosed as embodied in an automobile radiator construction.

5 An object of the invention is to provide an improved radiator of great cooling efficiency. Another object is to provide an improved radiator wherein the cooling effect of the front and the rear of the radiator is substantially 10 equalized.

To these ends and also to improve generally upon devices of the character indicated my invention consists in the various matters hereinafter described and claimed.

15 In the drawings, Figure 1 is a perspective view of a portion of a radiator unit.

Figure 2 is a vertical section of a portion of a radiator near the front.

Figure 3 is a vertical section of a portion of a radiator near the rear and

20 Figure 4 is a front view of a portion of the radiator.

The numerals 10 and 12 indicate corrugated sheet metal plates opposed to one 25 another in pairs to form interposed water passages 14. The plates 10 and 12 have folded fins 16 and 18, respectively, projecting away from the water passages in staggered relation, these fins forming portions of the walls of

30 connected air cells or passages 20 which extend from front to rear transversely of the water passages. A division plate 22 is inserted between each pair of water passages and, as herein shown, comprises a generally 35 zigzag plate the ridges of which meet the staggered fins 16 and 18. At intervals, portions of the division plate are struck up from opposite sides to form series of ridges 24 which form between them locating seats 26

40 for the folded fins. Striking up the ridges, of course, leaves perforated portions in the division plate so that air agitated by the ridges or otherwise can pass from one side of the division plate to the other.

45 The plates 10 and 12 have front and rear rows of end projections in the form of ridges 28 and 30, respectively, arranged in staggered relation on opposed plates so that the ridges of one plate enter the reentrant angles formed 50 by the ridges of the other plate where they are

secured, as by soldering. Preferably, a central row of ridges 32 may be formed on each plate to form spacing and stiffening means between front and rear water passages. Between the rows of ridges, the plates 10 and 55 12 have front and rear rows of parallel corrugations or cooling ribs 34 and 36, respectively, each rib being adjacent to a folded fin and joined by a substantially flat plate portion 38 to the next folded fin. The front 60 and rear rows of corrugations are preferably arranged unsymmetrically with respect to a central vertical plane so that each plate 10 and 12 has two rows of cooling ribs or blisters, each rib extending horizontally substantially 65 through one half of the length of each air passage, a cooling rib or blister 36 at the rear of the radiator being in alignment with a flattened portion 38 at the front and vice-versa.

This staggered, or out of alignment relation, of front and rear ribs produces a greater 70 cooling efficiency at the rear of the radiator.

75 For instance, in the usual radiator, cool air enters the air passages and extracts heat from the water at the front and as it immediately becomes considerably heated, it has little capability of extracting heat from the rear. In the present radiator, cool air is able to pass comparatively quickly over a flattened area 80 38 at the front without extracting the maximum amount of heat and in this comparatively cool condition it engages a cooling rib 34 at the rear and extracts considerable heat.

85 The cooling ribs are also unsymmetrically arranged with respect to the folded fins so that the resulting depressions in the water passages substantially oppose one another to form pockets 40 of larger water capacity than the connecting passages. Hence the flow of water is retarded and the time that the water 90 is in contact with the cooling ribs is increased. The corrugations or ribs increase the cooling area and strengthen the walls and the air currents are broken up better by the front-to-rear staggered relation of the ribs. Plates 95 10 and 12 may be separate plates or, as indicated in Figure 1, one plate 10 may be integrally united at the bottom, as by stiffening fold 42, to a plate 12 of the next preceding passage.

Although the invention has been disclosed by reference to a certain specific construction, it should be understood that, in its broader aspects, the invention is not necessarily limited to the form selected for mere illustrative purposes.

I claim:

1. A radiator structure comprising opposed plates forming an interposed water passage, the plates having folded oppositely projecting staggered fins defining walls of air passages and the portions of each plate connecting the fins having a plurality of rows of corrugations and end ridges with an intermediate row of ridges separating the rows of corrugations and spacing the plates, the ridges of the opposed plates being staggered and interfitting with one another, and the corrugations forming convex cooling ribs of large area extending lengthwise of and staggered in the direction of the air passages; substantially as described.

2. A radiator structure comprising opposed plates forming an interposed water passage, the plates having folded oppositely projecting staggered fins defining walls of air passages and the portions of each plate connecting the fins having a plurality of rows of parallel corrugations and end projections, the corrugations of each plate being unsymmetrically arranged with respect to axes extending longitudinally of the air passages whereby convex cooling ribs extend lengthwise of the air passages in staggered relation; substantially as described.

3. A radiator structure comprising opposed plates forming an interposed water passage, each plate having a plurality of rows of transversely extending corrugations and end ridges, the end ridges of the opposed plates being staggered and interfitting with one another, the corrugations of each plate being unsymmetrically arranged with respect to transversely extending axes to form staggered cooling ribs which extend transversely of the water passage on the exterior thereof; substantially as described.

4. A radiator structure comprising opposed plates forming an interposed water passage, the plates having oppositely projecting staggered fins defining walls of air passages and the portions of each plate connecting the fins having a plurality of rows of corrugations and end ridges with intermediate ridges between the rows of corrugations, one row of corrugations of each plate being unsymmetrically arranged with respect to the corrugations of the other row, the corrugations thereby forming staggered cooling ribs extending lengthwise of the air passages, said ribs on each plate also being arranged unsymmetrically with respect to the fins whereby the resulting depressions in the water passages substantially oppose one another to form pockets of larger capacity

than the connecting passages; substantially as described.

5. A radiator construction comprising spaced pairs of corrugated plates united at their front and rear edges, the plates of each pair being separated from one another between said edges to form vertical water passages, the spaces between adjacent pairs of plates forming horizontal air passages extending transversely of the water passages, and the corrugations of the front portions of the plates being out of horizontal alignment with the corrugations of the rear portions of the plates to equalize the cooling efficiency of the front and rear of the radiator; substantially as described.

6. A radiator structure comprising opposed plates forming an interposed water passage, the plates having folded oppositely projecting staggered fins defining walls of air passages and the portions of each plate connecting the fins having a plurality of rows of corrugations and end ridges, the end ridges of the opposed plates being staggered and interfitting with one another, and the corrugations forming convex cooling ribs of large area extending lengthwise of and staggered in the direction of the air passages; substantially as described.

7. A radiator structure comprising water tubes formed by sheets of corrugated metal soldered along their lateral edge portions, each sheet of metal having corrugations in slightly offset relation to the corrugations in the adjacent sheet whereby pairs of corrugations form enlargements in a water tube at an angle thereto.

8. In a radiator structure, a water tube having corrugated walls forming enlarged and contracted tube portions, the enlarged portions being disposed at a downwardly inclined angle to the tube whereby the direction of water flow is changed.

9. In a radiator structure, a water tube having corrugated walls forming enlarged and contracted tube portions, the enlarged portions being disposed at a downwardly inclined angle to the tube whereby the direction of water flow is changed and cooling fins on the said enlarged portions.

In testimony whereof I hereunto affix my signature.

NORMAN WALKER.
